(57) **CLAIM**

The ornamental design for a light string with remote control, as shown and described.

DESCRIPTION

FIG. 1 is an enlarged perspective view of a remote control of a light string with remote control showing my new design shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the light string of the light string with remote control shown separately for ease of illustration.

FIG. 10 is another exploded perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the light string with remote control where the remote control is shown with the light string;

FIG. 18 is an enlarged view of portion 18 shown in FIG. 9; and,

FIG. 19 is an enlarged view of portion 19 shown in FIG. 15. The light string is shown with symbolic breaks in its length, and the appearance of any portion of the light string between the break lines forms no part of the claimed design. The dash-dot broken lines in the drawings depict portions of the light string with remote control that form no part of the claimed design. The dot-dash broken lines represent boundaries of the enlarged portions and form no part of the claimed design.
